UNITED STATES PATENT OFFICE.

ROYAL L. HALL, OF OTSEGO, WISCONSIN.

BRUSH.

SPECIFICATION forming part of Letters Patent No. 611,249, dated September 27, 1898.

Application filed August 27, 1897. Serial No. 649,685. (No model.)

To all whom it may concern:

Be it known that I, ROYAL L. HALL, of Otsego, in the county of Columbia and State of Wisconsin, have invented a new and useful Improvement in Brushes, of which the following is a description, reference being had to the accompanying drawings, which are a part of this specification.

My invention relates to an improved brush that is particularly designed and adapted for brushing the hair or shampooing the scalp of a person; but a brush of substantially the same form and construction may be used for brushing the hair or fur of animals.

The invention consists of the device and its parts and combination of parts or their equivalents, as hereinafter described and claimed.

Figure 1 is a central longitudinal section of the complete device. Fig. 2 is a view of the complete device from that side which is at the bottom in Fig. 1. Fig. 3 is a detail showing a modified form of construction.

In a general way my improved device consists of a revoluble brush A, mounted in a case B. The brush A consists of a body C, preferably cylindrical in form, to which are affixed a large number of tufts of bristles D, preferably arranged in a number of series, each series extending from one end to the other of the body C. The tufts D are formed of stiff bristles or fine elastic wires or analogous material. The brush A is mounted revolubly in the case B, preferably by means of an axle E, extending longitudinally and axially through the body C, which is fixed thereon and has its bearings in the case B. This axle E is provided at one end with a cranked handle F, by which the operator may rotate the brush.

The case B, preferably constructed of sheet metal, consists of a chamber G at its front end of substantially such size and shape as to receive therein the brush A and permit its free revolution and an ancillary chamber H, extending rearwardly from the chamber G and being a continuation thereof in that direction. This chamber H is provided with an aperture closed by a door or slide I, which door is mounted on the case in such manner as to be adapted to slide freely thereon over the door-aperture, being thereby adapted to close the aperture or to be withdrawn there-

from. The slide I for this purpose is preferably provided with overturned flanges K K, which take onto corresponding flanges on the case B, whereby the two parts are held together movably.

An enlarged opening L in the case opposite the brush A permits the brush to be brought into contact with the hair or scalp at this opening. This opening is preferably located just in front of the chamber H, so that any dust or foreign matter taken up by the tufts of the brush is carried by the revolution thereof rearwardly and deposited in the chamber H, and the accumulations in that chamber may be removed from time to time by withdrawing the door I.

The case B at its front end is in curved form, and the aperture L, through which the bristles or tufts of the brush project, is so located that its walls are in convex form concentric with the axis of the brush and at such distance therefrom that no other adjacent part of the case projects farther from the axis of the brush; or, in other words, there is no adjacent projecting part of the case that would prevent the exposed part of the brush from being pushed into the hollows or depressions in the anatomy of a horse or other animal, so that the brush can get at the skin or hair in these depressions or hollows of the animal, where dust is most liable to settle and that are most important to clean by brushing. In fact, the case is so constructed and the brush is so located therein that the device can be used to clean all parts of an animal, even the hollows or depressions about the neck and shoulders and rear legs at the articulations with the body.

A more rapid rotation of the brush is sometimes desired, that can be readily got by rotating it by hand by means of the cranked handle F, integral with the axle E, on which the brush is mounted, and to accomplish this more rapid rotation readily a pinion M is put on the axle E and a larger pinion or cog-wheel N, meshing therewith and mounted on the side of the case, is employed in connection with a cranked handle F', fixed in the wheel N.

What I claim as my invention is—

A shampooing device, comprising a case formed at one end on a curve and having an

aperture across the case in the curved portion thereof, the curve being concentric with the axis of an inclosed cylindrical brush, said cylindrical brush in the case journaled in its side walls and closely inclosed by the case except at said aperture where said brush is exposed through the aperture and except at the rear where there is a dust-chamber, said dust-chamber in said case at the rear of

the brush, a door closing a door-aperture at 10 the rear of the dust-chamber, and means for rotating the brush.

In testimony whereof I affix my signature in presence of two witnesses.

ROYAL L. HALL.
